LAMP SHADE

Richard Lary, Lowell, Mass., assignor to
Hilda Erlich, Brooklyn, N.Y.

Filed June 8, 1973, Ser. No. 368,240

Term of patent 14 years

Int. Cl. D26—05

U.S. Cl. D48—16 E

The figure is a perspective view of a lampshade showing my new design, all sides being identical.

I claim:

The ornamental design for a lampshade, as shown and described.
